CLAIM

The ornamental design for a changing table for a baby, as shown and described.

DESCRIPTION

FIG. 1 is a perspective view of a changing table for a baby embodying my new design;

FIG. 2 is a front elevational view;

FIG. 3 is a rear elevational view;

FIG. 4 is a left side elevational view;

FIG. 5 is a right side elevational view;

FIG. 6 is a top plan view;

FIG. 7 is a bottom plan view; and

FIG. 8 is a perspective view of a changing table for a baby, showing a second embodiment of my new design.

FIG. 1

FIG. 2

FIG. 3

FIG. 4

FIG. 5

FIG. 6

FIG. 7

FIG. 8
